(57) **CLAIM**

The ornamental design for a bear figurine as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the bear figurine.

FIG. 2 is a back view of the bear figurine.

FIG. 3 is a right side view of the bear figurine.

FIG. 4 is a left side view of the bear figurine.

FIG. 5 is a left perspective view of the bear figurine.

FIG. 6 is a right perspective view of the bear figurine.

FIG. 7 is a top view of the bear figurine; and,

FIG. 8 is a rear view of the bear figurine.

The dashed broken lines disclosed in FIG. 8 depict portions of the bear figurine that form no part of the claimed design.
